UNITED STATES PATENT OFFICE.

SOLON O. RICHARDSON, JR., OF TOLEDO, OHIO.

DESIGN FOR A GLASS DISH.

SPECIFICATION forming part of Design No. 24,875, dated November 12, 1895.

Application filed July 21, 1894. Serial No. 518,276. Term of patent 7 years.

To all whom it may concern:

Be it known that I, SOLON O. RICHARDSON, Jr., of Toledo, county of Lucas, and State of Ohio, have invented a certain new and original 5 Design for Dishes; and I do hereby declare that the following is a full, clear, and exact description of the invention, which will enable others skilled in the art to which it appertains to make and use the same, reference being had 10 to the accompanying drawings, and to the figures of reference marked thereon, which form part of this specification.

My invention relates to a design for dishes, and pertains to the exterior surface ornamentation thereof.

Figure 1 is a plan view of the dish embellished with my design. Fig. 2 is a sectional elevation on line x x , Fig. 1.

The center of the dish is formed with a 20 hexagonal figure 1, on which are cut a series of prisms 2, radiating from the center of the dish. The lines forming the hexagon are extended, as shown, forming six triangular figures 3 opposite each side of the hexagonal center, the 25 two sides formed by the extension of the lines forming the hexagon having parallel lines 4 ornamenting the sides, the triangular space 5

being ornamented by intersecting cross-hatching. Between each triangular figure 3 are fan-shaped figures 6, each alternate figure 30 being embellished with prisms radiating outwardly from an angle nearest the center, the remaining figures having intersecting lines forming frusto-pyramidal-shaped projections 7, having a checkering upon the top.

The leading features of the design consist in the hexagonal center having a series of prisms on its face radiating from the center, the encircling triangles ornamented by intersecting lines, and the fan-shaped figures formed thereby, each provided with intersecting lines forming frusto-pyramidal projections, all as shown and described.

What I claim is—

The design for dishes, as herein shown, and 45 described.

In testimony that I claim the foregoing as my own I hereby affix my signature in presence of two witnesses.

SOLON O. RICHARDSON, JR.

Witnesses:

J. D. ROBINSON,
CARROLL J. WEBSTER.
